(57) CLAIM

The ornamental design for a plant stem covering as shown and described.

DESCRIPTION

FIG. 1 is a top perspective view of a first embodiment of a plant stem covering;

FIG. 2 is a bottom perspective view thereof;

FIG. 3 is a front view thereof;

FIG. 4 is a rear view thereof;

FIG. 5 is a top view thereof, the bottom view thereof being a mirror image;

FIG. 6 is a top perspective view thereof with an environmental structure shown in broken lines that is not part of the claimed design;

FIG. 7 is a top perspective view of a further embodiment of a plant stem covering, wherein the vertical lines indicate the color red;

FIG. 8 is a bottom perspective view thereof;

FIG. 9 is a front view thereof;

FIG. 10 is a rear view thereof;

FIG. 11 is a top view thereof, the bottom view thereof being a mirror image; and,

FIG. 12 is a top perspective view thereof with an environmental structure shown in broken lines that is not part of the claimed design.

The broken lines in FIGS. 6 and 12 represent environmental subject matter only and form no part of the claimed design.

1 Claim, 8 Drawing Sheets
